UNITED STATES PATENT OFFICE.

SYLVESTER F. WILSON AND AUGUST L. WAGNER, OF LOS ANGELES, CALIFORNIA.

SELF-PROPELLING BED-FAN.

1,233,155.

Specification of Letters Patent. Patented July 10, 1917.

Application filed September 6, 1916. Serial No. 118,687.

To all whom it may concern:

Be it known that we, SYLVESTER F. WILSON and AUGUST L. WAGNER, residing at Los Angeles, in the county of Los Angeles and State of California, have invented new and useful Improvements in Self-Propelling Bed-Fans, of which the following is a specification.

Our invention relates to improvements in self-propelling bed-fans; and the objects of our improvements are, to provide a fan which will operate automatically by the weight of the person using the bed; to suspend the spring of a bed within the frame 15 of the bed by a cable, cord, chain, or other suitable means, so as to operate a mechanism attached to the spring; to provide a suitable number of gears assembled in a frame which is attached to the spring of a bed so as to be put in motion by the weight 20 of a person using the bed causing a rotation of the fan connected with the gearing; the invention consisting in the construction, combination and arrangement of devices 25 hereafter more fully described and claimed, and illustrated in the accompanying drawing, in which—

Figure 1 is a side view of our device.

Fig. 2 is an end view of our device.

Similar numbers refer to similar parts throughout the papers.

The spring 1 of a bed is suspended within the bed frame 2 by a cable, cord, chain, or other suitable means 3 and 4, see Fig. 2. 35 The cable 3 is secured to the bed frame as indicated at 5 at one end and the other end of the cable is secured to an operating pulley 6, the connection being indicated at 7. The cable 4 is secured to the bed frame at 8 and 40 to the operating pulley 6 at 9. The small pulleys 10 and 11 are provided to prevent the bed spring from tipping, holding the spring in balanced horizontal position. The small pulleys 10 and 11 are turnably secured

45 to the spring. The operating pulley 6 is secured to a shaft 12, longitudinally disposed below the spring and journaled in the supporting plates 13 and 14, which are secured to the bed spring. Between the supporting 50 plate 13 and another plate 15, a suitable number of gears 16 are mounted to receive and transmit the turning motion of the shaft

12. A pair of bevel gears 17 transmit this motion to the vertical shaft 18, and another

pair of bevel gears transmits the motion to 55 a short horizontal shaft 19, to which fan 20 is secured.

The turning motion of the shaft 12 is caused by the weight of a person using the bed, the weight of the person acting on the 60 bed spring 1 by which it is transmitted to the cables 3 and 4 through the small pulleys 10 and 11, and the stress in the cables causes a rotation of the operating pulley 6, which is secured to the shaft 12.

65 The gears in this device are of such a proportion as not to allow any turning motion unless a certain weight is put on the bed spring.

The bed spring is raised to a position high 70 enough to allow an unwinding of the cables from the operating pulley 6. The cables are rewound by turning one of the shafts in the gears raising at the same time the bed spring. For the purpose of rewinding the cables, one 75 of the shafts is provided with a crank, or a square for a crank or key, not shown in the drawing but which will easily be understood as possible. The shaft 21, see Fig. 2, is indicated as preferable for this purpose.

80 Furthermore it will easily be understood that the gears can be of such proportion, and the reduction of the speed in the fan to the speed in the operating pulleys through the gears so as to cause the whirling of the fan 85 for several hours after a person entered the bed.

Having thus described our invention, we claim:—

1. In combination with a bed having a 90 frame and a spring, said spring suspended within the frame, a fan mounted above the bed spring, operating mechanism mounted below the bed spring being connected with the fan above the bed spring, and suspending means secured to the bed frame and operating mechanism serving as support for the bed spring.

2. In combination with a bed having a 100 frame and a spring suspended within the frame, a fan mounted on the bed spring, operating mechanism secured to the bed spring in connection with the fan, and suspending means connecting the bed frame with the operating mechanism supporting the bed 105 spring.

3. In combination with a bed having a frame and a spring suspended within the

frame, a fan mounted above the bed spring, a shaft mounted longitudinally below the bed spring, gears inserted between the shaft and the fan connecting the shaft with the 5 fan, pulleys secured to the ends of the shaft, and suspending means secured to the bed frame and the pulleys.

In testimony whereof we hereunto affix

our signatures in the presence of two witnesses.

SYLVESTER F. WILSON.
AUGUST L. WAGNER.
